UNITED STATES PATENT OFFICE.

JOHN F. PETERS, OF EDGEWOOD PARK, PENNSYLVANIA, ASSIGNOR TO WESTINGHOUSE ELECTRIC & MANUFACTURING COMPANY, A CORPORATION OF PENNSYLVANIA.

TRANSFORMER WINDING.

Application filed June 3, 1921. Serial No. 474,788.

To all whom it may concern:

Be it known that I, JOHN F. PETERS, a citizen of the United States, and a resident of Edgewood Park, in the county of Allegheny and State of Pennsylvania, have invented a new and useful Improvement in Transformer Windings, of which the following is a specification.

My invention relates to transformers and it has particular relation to a novel arrangement of windings therefor.

The object of my invention is to provide an arrangement of windings whereby the proportion of the total space occupied by the windings and insulation with respect to the space occupied by the active current carrying conductor in a transformer is reduced to a minimum.

In the construction of transformers, it has been found advisable to make the high tension coils embrace the low tension coils closely. In winding transformers, it has been customary to mount separate high tension windings on the individual legs of the core. In some instances, the mid-point of the high tension windings on each leg is connected to a source of potential and the end portions thereof are connected to ground. This connection permits of symmetrical distribution of insulation and results in two parallel current paths on each leg of the transformer. As each transformer has at least two legs, the high tension current must be divided into at least four paths. As each of these current paths has the full potential of the line to which it is connected impressed thereon, the insulation between the winding coils and the core and between adjacent turns of the same winding will be independent of the current carried thereby.

By means of my invention, I provide an arrangement of coils whereby a core having a plurality of legs is provided with a high tension winding which consists of but two parallel paths of relatively heavy cross-sectional area of which the high tension winding closely embraces the low tension winding. In such construction, the amount of insulation between the high tension and low tension windings is unchanged but the thickness of insulation between the adjacent turns of the high tension coils is reduced to a minimum.

In the accompanying drawings,

Figure 1 is a cross-sectional view of a transformer constructed in accordance with my invention, portions thereof being omitted for the sake of clearness.

Fig. 2 is a diagrammatic view of the structure illustrated in Fig. 1.

In the drawings, I show a transformer core 3 provided with two legs 4 and 5, respectively. Upon the leg 4 is mounted a plurality of coils 6 and the leg 5 is likewise provided with a plurality of coils 7. The coils 6 and 7 constitute the high tension winding, the low tension winding is shown in two sections 4a and 5b mounted on the legs 4 and 5, respectively.

The coils 6 and 7 are connected in series alternately by means of connections 8. The mid-point 9 of the winding thus formed is connected to a source of potential from which the energy is derived and the end portions 10 thereof are connected to ground as indicated at 11. The high tension current is thus divided into two paths, both of which are evenly distributed about all the legs of the core member.

In the event that the transformer core has more than two legs, the coils would be recurrently wound upon each of said legs successively, in the manner herein described in connection with a core of but two legs, the coils near the midpoint of the leg being always maintained at a higher potential than are those near the end of the legs. This construction permits of the use of symmetrical graded insulation between the high tension coil and the low tension coil and between the high tension coil and the core member.

By means of my invention, it will be apparent that it is possible to provide but two parallel paths for the high tension current irrespective of the number of legs on the transformer core. When the number of current paths is maintained at a minimum, the cross-sectional area of the conductors employed must necessarily be large. The amount of insulation necessary for properly insulating the high tension turns over the low tension turns is independent of the size of conductors. However, by the use of my invention, the thickness of insulation required between the individual turns of the high potential winding is greatly reduced.

and the space factor of the transformer is thereby reduced to a minimum.

While I have shown but a single embodiment of my invention, further changes and modifications may be made therein without departing from the spirit and scope thereof, and I desire, therefore, that only such limitations shall be placed thereupon as are imposed by the prior art or are specifically set forth in the appended claims.

I claim as my invention:

1. In a transformer, a core member provided with a plurality of legs, a winding successively recurrently wound upon said plurality of legs, the ends of said winding being maintained at ground potential, and substantially the midpoint thereof being connected to a source of electrical energy.
2. In a transformer, a core member provided with a plurality of legs, a plurality of coils disposed upon said legs, the coils of said legs being connected in series alternately, the coils adjacent to the midpoints of said legs being connected to a source of potential and the coils adjacent the ends thereof being maintained at substantially ground potential.
3. In a transformer, a terminal therefor, a core member having a plurality of legs and a plurality of coils on each of said legs, said coils being connected in two parallel groups between said terminal and a point of ground potential, each of said groups consisting of a plurality of coils on each of said legs connected alternately in circuit.
4. In stationary induction apparatus, the combination with a core having a plurality of winding legs, of a winding on each of said legs, a line terminal connected to intermediate points of all of said windings, and cross-connections connecting portions of all of said windings in series at each side of said intermediate points, whereby two similar paths in multiple leading from said line terminal are established in said windings.
5. In stationary induction apparatus, the combination with a core having two winding legs, of a plurality of groups of winding turns on each of said winding legs, two of said groups of turns near opposite ends of said core being connected to ground to provide one terminal of the apparatus, a high-voltage terminal connected to two of said groups of turns, each of said latter groups of turns being separated from the ends of said core by groups of turns of lower voltage, means connecting in series groups of turns on both of said winding legs between one of said grounded groups and one of said

high-voltage groups, and means connecting in series groups of turns on both of said winding legs between the other of said grounded groups and the other of said high-voltage groups.

6. In stationary induction apparatus, the combination with a core having two winding legs, of a plurality of groups of winding turns on each of said winding legs, cross connections connecting said groups of turns in series, said groups being disposed alternately on said winding legs, the two end groups of the series being grounded to provide one transformer terminal, and a second transformer terminal connected to said series connected groups of turns near the center thereof.

7. In stationary induction apparatus, the combination with a core having two winding legs, of a plurality of groups of winding turns on each of said winding legs, cross connections connecting said groups of turns in series, said groups being disposed alternately on said winding legs with the two end groups near opposite yokes of the core, said two end groups being grounded to provide one transformer terminal, and a second transformer terminal connected to said series connected groups of turns near the center thereof.

8. In stationary induction apparatus, the combination with a core having a plurality of winding legs, of a winding on each of said legs, a single line terminal connected to the central points of all of said windings, and cross connections for connecting portions of the winding on each leg in series with portions on every other leg at each side of said central points, whereby two similar paths in multiple for the current are established, each path traversing portions of the winding on each leg.

9. In stationary induction apparatus, the combination with a core having a plurality of winding legs, of high and low voltage windings on each leg, a single line terminal connected to the central portions of all of the high voltage windings, and cross connections connecting portions of the high voltage winding on each leg in series with portions of a high voltage winding on every other leg at each side of said central portions whereby two similar paths in multiple are established, each path traversing portions of the high voltage winding on each leg.

In testimony whereof, I have hereunto subscribed my name this 26th day of May, 1921.

JOHN F. PETERS.
